FLUID MEANS

Leland A. Borden, 540 E. Merrill Ave., Rialto, Calif.
Filed Sept. 8, 1959, Ser. No. 838,649
5 Claims. (Cl. 103—128)

The present invention relates to improved means and techniques for moving liquids and in its broader aspects is applicable to devices such as pumps, propulsion systems and the like wherein it is desired to produce movement of fluids. Also, the present invention in its broader aspects is applicable to prime movers wherein fluid in motion accomplishes useful purposes.

Briefly, the arrangements described herein involve two oppositely rotating shafts upon which are arranged mating generally spiral convolutions for either pumping fluid in pumps or prime movers; and in each case the convolutions in each shaft are housed within a snugly fitting casing which in some cases may taper in a direction of the inlet to the outlet.

An object of the present invention is to provide improved devices of this character useful either as pumps or prime movers.

Another object of the present invention is to provide an improved pump structure which does not require seals of plastic or rubber material and thus may be used at very high or very low temperatures.

Another object of the present invention is to provide an improved pump of this character in which two meshing elements are rotated and in operation have pockets formed near the circumference to entrap fluid while rotating so as to expel fluid that enters an inlet into and through an outlet opening.

Another object of the present invention is to provide a fluid device of this character using intermeshed rotary spiral screw members for blowers, pumps, compressors, motors and the like.

Another object of the present invention is to provide an improved device of this character using mating helical impellers or pistons so constructed that compensation may readily be made to achieve proper mating of parts either in the initial manufacture or after subsequent use and wear.

Another object of the present invention is to provide an improved arrangement of this character which is particularly useful in a propulsion system as, for example, in a system for propelling boats.

The features of the present invention which are believed to be novel are set forth with particularity of the appended claims. This invention itself, both as to its organization and manner of operation, together with further objects and advantages thereof, may be best understood by reference to the following description taken in connection with the accompanying drawings in which:

FIGURE 1 is a transverse sectional view through a device which is either a prime mover or a pump and which incorporates features of the present invention.

FIGURE 2 is a sectional view taken substantially on the line 2—2 of FIGURE 1.

FIGURE 3 is a transverse sectional view similar to FIGURE 1 but of a modified structure.

FIGURE 4 illustrates a construction embodying features of the present invention on a boat.

2

FIGURES 5, 6 and 7 are sectional views taken on lines 5—5, 6—6 and 7—7 respectively in FIGURE 4.

The device shown in FIGURE 1 incorporates generally three casing sections 10, 11, 12, the sections 10, 11 being bolted together by bolts 14 and the sections 11 and 12 being bolted together by bolts 15. The housing or casing 10 has a pipe threaded opening 16 which serves as an outlet when the device is being used as a fluid pump and this opening serves as an inlet when the device is being used as a prime mover. Simultaneously, the casing 12 has an opening 17 which serves as an inlet when the device is being used as a pump and which serves as an outlet when the device is being used as a prime mover.

Snugly received within the center casing section 11 are two intermeshed rotary screw members 20 and 21. These members 20 and 21 are rotated in opposite directions and in accordance with one important feature of the present invention, the axes of rotation of the two members 20 and 21 are inclined one with respect to the other for achieving important advantages.

For these purposes the reduced shaft end 20A is journalled for rotation in the bushing 24 in casing section 10; and the other shaft end 20B of the member 20 is rotatably supported in the bushing 26 threaded in the casing section 12 with the reduced end of such shaft 20B having secured thereto the bevel gear 28 meshing with a like bevel gear 29 on the driving shaft 30.

This drive shaft 30 corresponds to the shaft of the member 21 and such member 21 is rotatably mounted like previously described member 20. Thus, the shaft end 21A is rotatably mounted in the bushing 33 in the casing section 10 and the drive shaft is rotatably mounted in the bushing 34 threaded in the casing section 12. Preferably O-rings 38 and 39 surrounding shafts 20B and 30 respectively and being pressed against an inner wall of casing section 12 by corresponding threaded bushings 26 and 34, serve as sealing members.

As indicated previously, the rotational axes of the members 20 and 21 are inclined with respect to one another and this is clearly shown in the drawings. For this reason and also to achieve other advantages, the inner wall of the center casing section 11 has two inter-communicating circular sections 11A and 11B (FIGURE 2) which snugly receive the members 20 and 21 respectively; and such sections 11A and 11B are tapered as indicated in FIGURE 1. The spiral convolutions on the members 20 and 21 are of the same diameter throughout the length of the members 20 and 21. The degree of fit of the members 20 and 21 within the casing 11 is conveniently adjusted using spacers or shims 40 of different thicknesses, these spacers or shims 40 being clamped between adjacent flanges of the casing sections 11 and 12.

It is noted that the annular shoulders 20C and 21C on shafts of members 20 and 21 respectively are spaced somewhat from the bushings 24 and 33 to allow the members 20 and 21 to be moved further to the right in FIGURE 1, if so desired during initial manufacture or after subsequent use and wear. Such movement is accomplished by, for example, using a shim or spacer 40 of smaller thickness so that when the device is assembled and the bolts 15 are tightened, the casing section 12 engaging shoulders 20E and 21E of members 20 and 21 respectively causes the members 20 and 21 to be moved further to the right in FIGURE 1 within the casing 11. By these means the relative spacing between the members 20 and

21 as well as the relative spacing between these members and casing 11 may be conveniently adjusted.

It will be seen from the drawings that in operation of the device shown in FIGURE 1 (assuming that the same operates as a pump), fluid entering the inlet 17 and flowing into the space 42 within casing section 12 is pressurized in the space between the mating convolutions of the oppositely rotating members 20 and 21 and that such fluid after being pressurized enters the cavity 43 within casing 10 which is in communication with the outlet opening 16. The arrangement shown in FIGURE 1 is considered to be a high pressure-low volume pump as distinct from the medium-pressure-medium volume pump presently described in connection with FIGURE 3.

In FIGURE 3 the unit is assembled as in FIGURE 1 and those parts in FIGURE 3 corresponding to those in FIGURE 1 are given the same reference numeral raised, however, by 100. Thus, in FIGURE 3 the screw-type impellers corresponding to impellers 20 and 21 have the reference numerals 120 and 121. It will be noted in FIGURE 1 that the thickness of the impeller convolutions is much greater than in FIGURE 3 and that the thickness of the convolution in FIGURE 1 is substantially equal to the spacing between adjacent sides of adjacent convolutions on the other impeller. This means that in FIGURE 1 one convolution of an impeller substantially completely fills the space between adjacent convolutions of the other impeller. In other words, there is in effect a double seal provided between one convolution on one impeller and two convolutions on the other impeller. In FIGURE 3 the thickness of the impellers is not as great as in FIGURE 1 and there is only in effect a single seal. Hence, the arrangement shown in FIGURE 1 is capable of higher pressure operation, whereas in FIGURE 3 lower pressures only may be accommodated but at the same time the spacing between convolutions allows the handling of greater fluid flows. For that reason the arrangement shown in FIGURE 3 is characterized as a medium pressure-medium flow unit.

Observing the construction of FIGURE 3, it is noted that the so-called single seal is provided between, on the one hand, one side of one convolution and, on the other hand, the end of a convolution of the other impeller. This seal, as in FIGURE 2, is on a line extending transversely through the unit in FIGURE 3.

FIGURES 4-7 illustrate another form of the invention but specifically for impelling a boat 200. The boat includes a conventional gasoline driven engine 201 having its output shaft 202 geared to produce rotation of the shafts 204 and 205 in opposite directions. For this purpose there is a gear housing 206 in which there is a gear 207 mounted on shaft 202 and meshing with the gear 208 on shaft 204. A second gear 209 on shaft 204 meshes with the gear 210 on shaft 205. Thus, the shafts 204 and 205 are driven at the same speed through the gear reduction unit 206, i.e. the shafts 204, 205 rotate at a slower speed than the speed of the engine shaft 202. However, as indicated above, the rotation of these shafts 204 and 205 are rotated in opposite directions.

In general, the speed of the shafts 204 and 205 is not critical but is related to the pitch of the impellers 212, 213 mounted respectively on the shafts 204 and 205. The speed at which these impellers are driven is related, of course, to the speed at which it is desired to drive the boat 200 and it is believed that one skilled in the art appreciates the relationship between impeller pitch and boat speed and available engine power.

In accordance with an important feature of the present invention, these two impellers constructed generally as shown in FIGURE 3 with a seal between adjacent convolutions of adjacent impellers are housed within a housing 215. The shape of the housing 215 is best seen in FIGURE 5 and it is noted that in general it includes two partial cylinders joined at the points 216 and 217, this housing 215 being shaped so as to provide an inner sur-

face that conforms, with a close fit, with the peripheral portions of the impellers 212 and 213. It is desired that the clearance between these two peripheral portions and the housing be as small as practicable but the closeness of fit between adjacent convolutions of adjacent impellers is of greater importance. Instead of the impellers 212 and 213 being rotated about an inclined axis as in FIGURES 1-3, the axes of rotation extend generally parallel with the shafts 204, 205 being journaled in corresponding bearings 218 and 219 mounted on the housing 215. This housing 215, as shown in FIGURE 4, is bolted by means of bolts 222 to the stern of the boat 200 such that the driving shafts 204 and 205 are inclined generally rearwardly and downwardly as illustrated in FIGURE 4.

While in some cases it may be desired to tilt the axes of the driving shafts 204 and 205 as illustrated in FIGURE 4, in other cases it may be desired to mount the driving shafts 204 and 205 such that their axes are horizontal or more horizontal than illustrated in FIGURE 4. In other cases it may be desirable to extend the housing 215 more rearwardly than shown in FIGURE 6 and also to project such extension upwardly.

While the housed impeller arrangement is described specifically in connection with the propulsion of a boat in FIGURE 4-7, it will be understood that the arrangement may be used for other purposes such as for propelling a stream of air in a wind tunnel, ventilating systems or in any other system wherein it is desired to propel a stream of fluid either of the compressible or non-compressible type.

Also, while a gear bore has been shown for driving the shafts 204, 205, other means may obviously be used for producing equal rotation of the shafts in opposite directions.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A fluid unit of the character described comprising a housing, a pair of impellers having helical convolutions in said housing in mating relationship thereto, bearing means mounting said impellers for rotation on said housing with the axis of rotation of one of the impellers being inclined with respect to the axis of rotation of the other impeller, and means adjustably positioning said bearing means in said housing for axial movement with respect to said impellers to adjust the inclination of the shafts relative to each other.
2. A unit as defined in claim 1 in which said impellers each have helical convolutions of substantial thickness with adjacent sides of one impeller mating with adjacent sides of adjacent convolutions of the other impeller.
3. A unit as defined in claim 1 in which the spacing between adjacent convolutions of the impellers is greater than the thickness of a convolution.
4. A unit as defined in claim 1 in which the thickness of the convolutions of the two impellers is substantially equal to the spacing between adjacent sides of adjacent convolutions.
5. A unit as defined in claim 1 in which each of the impellers has shaft prolongations and said housing has two parts, one of said housing parts journailling one of said shaft prolongations and the other housing part journailling the other shaft prolongation for rotation, and said adjustably positioning means comprising shims between the housing parts.
